UNITED STATES PATENT OFFICE.

WILLIAM EATON PERRYCLEAR, OF SAVANNAH, GEORGIA, ASSIGNOR OF ONE-HALF TO
LUTHER W. HIGH, OF WILSON, NORTH CAROLINA.

STOVE.

1,299,020.

Specification of Letters Patent.

Patented Apr. 1, 1919.

Application filed March 13, 1918. Serial No. 222,141.

To all whom it may concern:

Be it known that I, WILLIAM EATON PERRYCLEAR, a citizen of the United States, residing at Savannah, in the county of Chat-
ham and State of Georgia, have invented
certain new and useful Improvements in
Stoves; and I do hereby declare the following
to be a full, clear, and exact description
of the invention, such as will enable others
skilled in the art to which it appertains to
make and use the same.

This invention relates to stoves and furnaces and more particularly to that type of stove shown in my former Patent 1,239,514, issued Sept. 11, 1917.

The object of this invention is to improve upon and simplify the construction shown therein.

One of the objects of the invention is the provision of concentric grates independently operable, and an improved arrangement thereof.

Still another feature of the invention resides in simplifying the means for preventing escape of the dust when the ash-pan is withdrawn.

Another object is to provide positive means to prevent withdrawal of the pan when the ash-exit is open. The invention further consists in the arrangements and combination of parts thereof disclosed in the following specification and specifically set forth in the appended claims.

And while it is clear that the present drawings illustrate the preferred form of my invention, the same is not restricted thereto but may be changed in design, size and mode of operation within the scope of such claims.

Referring to the drawings Figure 1 is a sectional elevation showing the general arrangement of the stove; Fig. 2 is a section on line 2-2 of Fig. 1 in the direction of the arrows; Fig. 3 is a detail view of the operating lever and its shaft connection; Figs. 4, 5 and 6, are detailed views showing the pan locking device. Fig. 7 is an enlarged plan view of the grate construction, and Fig. 8 is a vertical section of Fig. 7.

The stove or furnace which may be of any type, is provided with a grate preferably consisting of outer and inner members. The outer member comprises an outer wheel-shaped structure having a rim 2 joined to a hub 3, by means of radial spoke-like mem-

bers 4 which as illustrated are humped centrally as at 5 and rounded laterally across the top thereof to facilitate the passages of the ashes through said members when the grate is moved. The hub 3 is provided with a central recess 6 and a seat 7 on which rests the inner grate member 8 which may take various forms but herein is shown as provided with radially spaced arms or spokes 9 emanating from a central hub 10, the underside of which is provided with a recessed collar 11. Arm 9 shapes or curves radially and laterally downwardly from the hub which construction also insures the easy passage of the grate member.

To provide means to operate the outer grate member the same is preferably provided on the underside of the rim 2 with teeth 12 adapted to engage the teeth of one or more pinions 13 journaled as at 14 in the furnace wall. One of these pinions 15 is provided with a drive shaft 16 adapted to be turned in any manner. It is of course obvious that any type of gearing may be used and that the drawing contact need not necessarily be at the exact location shown. If desired, the grate may be made of a single member and rotated by the central shaft 17 as illustrated.

Means are also provided to independently operate the inner grate member 8 and the particular form illustrated is a shaft 17 projecting into the recess of the collar 11, and preferably provided with a yieldable connection of the pin and notch type so that the shaft can rotate relatively to the inner grate by having the pin thereon ride out of the notch in said collar 11 in case the grate is prevented from rotation by clogging.

Arranged below the grate is a draft device 95 which preferably consists of a series of openings 18 in the furnace wall at this point. And adapted to coöperate therewith is an annulus 19 provided with similar shaped openings 20 so that by oscillating this ring-shaped member the draft may be opened, closed or partially closed. It is also apparent that any convenient arrangement of draft device may be used in this connection.

In order to provide a suitable bearing for the vertical shaft 17 the walls of the furnace are provided with one or more inwardly curved ribs 21 formed with a centrally arranged bearing 22 through which the shaft 17 is journaled.

Fixed to said shaft 17 in any desired manner and immediately below said journal 22 is a collar 23 which, as shown in Fig. 3, comprises a lower enlarged ledge 24 and an upper standing stud 25 of circular form except that two of the sides thereof are cut away to provide the opposed flat faces 26.

Projecting through a slot 27 in the oscillatable annulus 19, and also passing through a much longer slot 28 in the wall of the furnace, is the lever 29 provided on its inner end with a yoke in the shape of an annulus which is adapted to rest on the ledge 24 and provided with a circular portion 30 surrounding and freely fitting the mutilated circular stud or projection 25 so that movement of the lever 29 in such position will not affect the shaft 17, but will oscillate the shaft annulus 19. The walls of the yoke or annulus project radially from the circular portion thereof as at 31 to form a flat-sided guide 32 to receive the flat faces of the circular stud 25 so that when the lever is pushed inwardly the stud 25 will enter into the guide 32 on the lever 29 in which position lateral movement of the lever will not only oscillate the draft annulus 19, but will also oscillate the shaft 17 to move the inner grate member.

At the lower portion of the furnace the walls thereof are preferably flared inwardly as at 33 to provide an ash exit 34 which is adapted to receive an ash-pan 35 of any suitable type. In the present instance the latter is shown as provided with an outwardly flaring mouth 36 adapted to make a dust-proof fit with the inwardly flaring mouth 37 of the ash exit.

In order to retain the base in such position and also permit its facile withdrawal, there is provided the ash support or base 38, herein shown of any appropriate design; and adapted to be supported from the base frame 39 of the furnace by means of the bracket members 40 which are pinned to a circular cross bar 41 also pivotally mounted in the furnace walls as at 42.

Depending from said base frame 39 is a spring catch 43 adapted to hold said base in its upper position to support the ash-pan, as shown in Fig. 6.

With this construction when the catch is released the base may be lowered whence the mouth of the pan 35 will slip off the flared mouth of the ash-exit.

To the end that ashes may not fall upon the floor when the pan is withdrawn there is provided a closure for the ash exit which consists of a perforated web 43 inserted into the lower portion of the ash exit and centrally recessed to provide a journal for the lowermost end of the vertical shaft 17. To the end of this shaft is fastened a co-operating shutter or ash exit closure 44 provided with spaced closing vanes 45, the upper

faces of which slant laterally from a central ridge 46, whereby to direct the ashes below. Above the shutter and integral therewith, or fast to the shaft 17, is the ash agitator 47.

Means is also provided for preventing the opening of said shutter except when the pan is in position and the same preferably comprises an arm 48 fast to shaft 41 and provided with a somewhat elongated locking pin 49 passing freely through the mouth of the ash exit and adapted to enter an aperture 50 in one of the shutter vanes 45 when the latter registers with the inwardly projected position of said locking pin, as shown in Fig. 4.

There is also provided means to prevent said pin from entering its slot 50 in the vane in any other but closed position, and in the present instance consisting of an abutment or shoulder 51 arranged on the shutter circumferentially thereof and adapted to lie in the path of said locking pin 49 as the shutter is oscillated, as illustrated in Fig. 5, so that in open position said pin will be forced outward and by its connection with shaft 41 will permit rotation thereof to allow the pan to be lowered.

It is patent that various arrangements of interdependently operated ash-exit closing and pan-locking devices may be adapted to my present form of stove and the construction above illustrated is but one embodiment of my invention.

In the operation of the device, when it is desired to regulate the draft, the lever 29 is pulled outwardly to disengage the flat-faced lug 25 from the guide 32 on the yoke, so that the shaft 17 will be unaffected, but engagement of the lever with the slot 27 will move the draft annulus 19. When it is also desired to operate the inner grate member 18, the lever 29 is pushed in, whence the shaft 17 may be rotated thereby to move the grate. In any position other than extreme movement of the lever 29 to the right, as shown in dotted lines in Fig. 2, the ash exit closure will be open, more or less, and the ashes free to fall into the pan. It will of course be clear that when the grate is operated the draft will also be open to assist the agitation of the fire.

When it is desired to remove the ash-pan the lever 29 must be forced to its extreme right, shown in dotted lines in Fig. 2, whence the ash-exit shutter will close, and the locking-pin 49 will automatically enter its aperture or notch 50 in the same, permitting the base to be free to swing downwardly and allow the pan to slide forwardly upon release of the spring catch.

Having thus described my invention what I claim as new and desire to secure by Letters Patent is:—

1. A grate comprising outer and inner concentric rotatably mounted sections and

means for rotating said sections either independently or together; said means consisting of an oscillating, longitudinally movable lever and means on the grate sections for engaging and adapting said lever in one position to rotate said sections simultaneously and in another position to rotate one section independently of the other.

2. In combination, a grate comprising an outer circular rotary section having a rim, a centrally recessed hub portion, and radial spoke-like members connecting said rim and hub portion, and a circular rotary grate section having radial spoke-like arms seated in said recess, and an oscillating lever provided with means movable into and out of locking engagement with means on said grate sections whereby said lever is adapted to rotate one grate section independently of the other or both simultaneously.

3. A grate comprising concentric outer and inner rotatable sections, the outer section having a centrally arranged ring-like hub portion, provided with an annular recess, and said inner grate section seated in said recess overlying the circular opening through said hub portion, together with means for rotating said outer and inner sections simultaneously; said means being movable and adapted in one position to rotate one section of the grate independently of the other.

4. The combination, in a furnace, of a movable grate, draft regulating means operable independent of the grate, and means for operating said draft regulating means independently of the grate; said means being adapted to connect and operate both the draft regulating means and grate simultaneously.

5. In a furnace, a grate and draft regulating means therefor, in combination with an oscillating lever movable longitudinally into position for operating said draft means alone or both the draft means and grate simultaneously.

6. A rotary grate consisting of a plurality of revolvably mounted sections, in combination with a longitudinally movable and laterally oscillating lever adapted in one position to rotate one section only of the grate and movable into engagement with another section for rotating the latter simultaneously with the former.

7. In a furnace, a rotary grate comprising a circular centrally recessed outer section having driving means thereon, an inner circular grate section seated in said centrally recessed portion of the outer section, driving members journaled in the walls of said fur-

nace engaging said driving means and adapted to rotate said grate, and means operatively connected with said outer and inner sections for rotating them either separately or simultaneously, as desired.

8. In combination with a rotary grate, a rotary draft regulating device, and a movable lever and operating means adapted in one position of the lever to operate said draft device alone and in another position of the lever to operate both grate and draft device.

9. In combination, a rotary grate, a rotary draft regulating device and an adjustable lever and coöperating means whereby said lever is adapted in one position to operate said draft device alone and in another position to operate both the grate and the draft device.

10. In combination, a rotary grate comprising concentric inner and outer rotary sections, an adjustable lever and coöperating means whereby said lever is adapted in one position to rotate both sections of the grate and in another position to rotate one section only of the grate together with a rotary draft regulating device operable by means of said lever simultaneously with the rotation of the grate.

11. A grate composed of a plurality of concentric rotatably mounted members, one member being provided with a hub portion and a rim and spaced ribs connecting said hub and rim, and said hub portion having an opening therethrough, and another grate member seated over said opening, together with movable means adapted in different positions to rotate said members either independently or together, as desired.

12. In combination, a grate comprising a plurality of movably mounted sections, an independently movable draft regulating device, and a movable lever adapted in one position to move said draft device alone and in another position to move both the draft device and said movably mounted members of the grate.

13. In combination, a movable grate, a movable draft regulating device therefor, and movable means for moving said grate and draft regulating device simultaneously; said means being adapted to be moved into inoperable relation to said grate and to operate said draft regulating device alone.

In testimony whereof I affix my signature in the presence of two witnesses.

WILLIAM EATON PERRYCLEAR.
